UNITED STATES PATENT OFFICE.

RUDOLPH C. SMITH, OF YONKERS, ASSIGNOR TO OTIS BROTHERS & CO., OF NEW YORK, N. Y.

VALVE FOR HYDRAULIC ELEVATORS.

SPECIFICATION forming part of Letters Patent No. 339,816, dated April 13, 1886.

Application filed November 12, 1883. Renewed October 22, 1884. Serial No. 146,229. (No model.)

To all whom it may concern:

Be it known that I, RUDOLPH C. SMITH, a citizen of the United States, and a resident of Yonkers, Westchester county, New York, have 5 invented certain new and useful Improvements in Valves for Hydraulic Elevator-Engines, of which the following is a specification.

My invention has for its object to prevent the noise and other injurious effects resulting 10 from the discharge of water under pressure into pipes, through which it is conveyed into tanks or other receptacles; and my invention consists in means, fully described hereinafter, whereby to maintain a pressure in the receiving 15 or discharge-pipe about equal to that in the vessel or pipe from which the water is discharged.

In order to illustrate my invention I have shown, in the accompanying sectional drawing, 20 sufficient of an Otis hydraulic elevator to explain the difficulties resulting from the discharge of water under pressure and the mode by which I remedy them. It should be understood, however, that my invention is applicable 25 in any case where water is discharged under pressure into a conduit.

The cylinder A contains the usual lifting-piston, B, and communicates at the upper end with a circulating pipe, C, at the lower end, 30 through a pipe, H, with the casing I, containing the usual piston or water-discharge valve, J, and the lower end of the circulating-pipe also communicates with said casing, all as in the Otis elevator above referred to, the construction, arrangement, and operation of the parts being too well known by those skilled in 35 the art to require further description.

In the class of apparatus above referred to it is found that the flow of water under pressure 40 from the space x beneath the piston through the contracted opening afforded by the partial lifting of the valve, and into the discharge-pipe K, (where there is frequently little, if any, pressure,) results in a loud whistling or hissing sound, which is not only disagreeable but 45 objectionable in other respects. This effect results from the difference of pressure in the space x and pipe K, and I have found that it can be overcome by equalizing the pressure in 50 the said places. To effect this result, I place an automatically-operating valve, a, at the end

of the discharge-pipe and below the surface of the water in the tank L, which valve, while it will yield to permit the passage of the discharge-water into the tank, will throttle the 55 discharge-opening to such an extent as to maintain the water in the pipe K under pressure either equal to that in the space x or so nearly the same that its flow from one space to the other is effected without noise or disturbance.

The automatic lifting of the valve a toward its seat may be effected by any of the usual means; but I prefer to connect the valve to the stem of a piston, b, adapted to a cylinder, 65 M, which communicates through a pipe, N, with the space x, so that pressure in the latter will act to close the valve against its seat and impart increased resistance to the action of the discharge-water in proportion as the pressure 70 in the space x increases.

To properly regulate the action of the valve, I provide the pipe N with a cock, E; and to equalize the pressure upon the valve J, I connect the pipe K by means of a tube, D, with 75 the space in the casing I above the valve.

Should any accident occur to the valve a the water may be cut off from the cylinder M by turning the valve E.

Without confining myself to the precise construction of parts illustrated and described, I claim—

1. The combination, with a water-discharge valve and with the discharge-pipe leading therefrom in a tank, of an automatically-operated regulating-valve arranged at the end of 85 said pipe within the tank, to throttle the passage of the discharge-water and secure a pressure in the said pipe about equal to that in the space or chamber through which the water 90 flows to the discharge-valve, substantially as described.

2. The combination, with the discharge-valve, discharge-pipe leading to a tank, and regulating valve at the end of the latter within 95 the tank, of a pipe, N, and means, substantially as described, whereby the water from the space or chamber through which water flows to the discharge-valve is brought to act upon the regulating-valve, substantially as 100 described.

3. The combination of the discharge-valve,

discharge-pipe leading to a tank, regulating-valve within the tank, and pipe D, connecting the discharge-pipe and space above the discharge-valve, whereby the pressure on said discharge-valve is regulated, substantially as described.

4. The combination, with an elevator-cylinder, water-discharge valve, the discharge-pipe leading therefrom, and a tank, of an automatically-operated regulating-valve arranged at the end of said pipe within the tank to throttle the passage of the discharge-water

and secure a pressure in the said pipe about equal to that in the space or chamber below the piston of the elevator, through which the water flows to the discharge-valve, substantially as described.

In testimony whereof I have signed my name to this specification in the presence of two subscribing witnesses.

RUDOLPH C. SMITH.
